DESIGN FOR A SURFACE SANDER

Joseph L. Feild, Detroit, Mich.

Application June 8, 1945, Serial No. 119,981

Term of patent 14 years

(Cl. D37—1)

To all whom it may concern:

Be it known that I, Joseph L. Feild, a citizen of the United States, residing at 12264 Washburn Avenue, city of Detroit, in the county of Wayne and State of Michigan, have invented a new, original, and ornamental Design for Surface Sander, of which the following is a specification, reference being had to the accompanying drawing, forming part thereof.

In the drawing:

Fig. 1 is a side view of the surface sander showing my new design;

Fig. 2 is an end view of the same; and

Fig. 3 is a plan of the same.

I claim:

The ornamental design for a surface sander, as shown.

JOSEPH L. FEILD.
